DESIGN FOR A COMBINATION LABORATORY UNIT

Thomas L. King, New York, N. Y., and Richard H. Butler, Westfield, N. J., assignors to Merck & Co., Inc., Rahway, N. J., a corporation of New Jersey

Application October 15, 1941, Serial No. 103,766

Term of patent 14 years

To all whom it may concern:

Be it known that we, Thomas L. King and Richard H. Butler, citizens of the United States, residing respectively, at New York, in the county of New York and State of New York, and at Westfield, in the county of Union and State of New Jersey, have invented a new, original, and ornamental Design for a Combination Laboratory Unit, of which the following is a specification, reference being had to the accompanying drawing, forming a part thereof.

The figure in the drawing is a perspective view of a combination laboratory unit, showing our new design, the opposite side of the unit being like the side shown.

We claim:

The ornamental design for a combination laboratory unit, substantially as shown and described.

THOMAS L. KING.
RICHARD H. BUTLER.
